WATSON S. LENNON, OF TUCSON, ARIZONA TERRITORY.

CAR-COUPING.

SPECIFICATION forming part of Letters Patent No. 709,338, dated September 16, 1902.

Application filed February 17, 1902. Serial No. 94,519. (No model.)

To all whom it may concern:

Be it known that I, WATSON S. LENNON, residing at Tucson, in the county of Pima and Territory of Arizona, have invented a new and Improved Car-Coupler, of which the following is a specification.

My present invention embodies certain improvements of draw-bar and connections for joining it with the draft-beams of the car-frame and whereby provision is made for lateral swinging of the draw-head with its co-operating coupling devices and for automatically returning said head to its straight-way position and for holding it to said position while traveling over a straight track-section.

My invention in its more subordinate features consists in certain details of construction and novel arrangement of parts, all of which will hereinafter be fully described, and specifically pointed out in the appended claims, reference being had to the accompanying drawings, in which—

Figure 1 is a perspective view of a portion of a car-body with my improved draw bar and head attached. Fig. 2 is a perspective view of the draw bar and head, the coupling-jaw being shown swung out. Fig. 3 is a longitudinal section thereof, taken practically on the line 3 3 of Fig. 5. Fig. 4 is a horizontal section of the same on the line 4 4 of Fig. 3. Fig. 5 is a transverse section of the head on the line 5 5 of Fig. 4, the gravity-lock for co-operating with the knuckle-jaw being shown in position for locking the said jaw when turning on curves. Fig. 6 is a diagram illustrating the correlation of the fulcrum portions of the coupling-jaw and the interlocking members on the draw-head ears when the jaw is in its coupled position. Fig. 7 is a perspective view of the coupling-jaw. Fig. 8 is a similar view of one of the draw-head ears in which the coupling-head is fulcrumed. Fig. 9 is a plan view illustrating the relative position of the draw-head, the draw-bar, and the draw-bar-attaching devices when on curves. Fig. 11 is a transverse section taken on the line 11 of Fig. 4. Fig. 10 illustrates the position in which the connecting straps or bands joined with the draw-bar are turned to disengage them from the draw-bar. Fig. 12 is a detail view of said straps or bands de-

tached. Fig. 13 is a detail view of the swinging spring-pressed block.

In the present form of my invention the draw-head 10 in its general contour is of the "Janney" type, it having at one side the guide-horn 10^a and at the opposite side a pair of ears 10^b, between which the knuckle or coupling member A is fulcrumed in a manner presently explained. At the side adjacent the horn 10^a the draw-head mortise has a vertical wall 10^c, that forms the lower continuation of one side of a housing or pocket 10^d, formed in a cap portion 10^e, integrally cast with the top of the draw-head and which is provided to receive a vertically-movable and gravity-dropped locking-block 11, having a socket 11^a to receive the end 12^a of a U-shaped lift-lever 12, detachably connected to the block 11 by the cotter-pin 11^x, as shown. The member 12^a passes down through an aperture 12^x in the bottom of the draw-head and merges with the long arm 12^c, that extends up through a guide-aperture in the horn part 10^a of the draw-head, its upper end being flattened, as at 12^d, and apertured to receive the end of a lift clevis, hook, or chain capable of being operated from the top or sides of the car in any well-known manner.

On the upper and lower walls of the draw-head mortise are formed opposing raised surfaces b b', whose front edges b^x and rear edges b^y are curved on a plane concentric with the axial point of the coupling member A, provided with channels a a' in the upper and lower surfaces of its inner or neck portion, the opposite edges of which are positioned to engage and co-operate with the edges b^x and b^y of the surfaces b b' of the draw-head. At its extreme outer edge the inner end of member A has a depression a^x, adapted to engage with the gravity-block 11 in the manner and for the purpose presently described.

By referring now more particularly to Figs. 6 to 9, it will be noticed the inner face of the two ears 10^b each have a projection 10^e 10^c, whose outer and inner edges e f are in planes at right angles to each other, and the inner edge e', between said edges e f, is concaved on an arc of a circle, and the said two projections 10^e are so disposed as to co-operate with semicircular bearing portions a⁵ a⁵ on the upper and lower faces of the

neck of the coupling-jaw A, which faces also have bearing members a^6 a^6 , disposed at points diagonally inward from the bearings a^5 .

By providing the ears 10^b with projections 10^e and the neck of the jaw A with bearing portions a^5 a^5 , as described and shown, a very simple and effective means is provided for detachably fitting the jaw A between the ears 10^b 10^b and providing a fulcrum or hinge 10 connection therefor without the use of pivot-pins and the like. To fit the coupling-jaw in place, the neck thereof is slipped between the ears 10^b and the bearings a^5 are moved into engagement with the concaved face e' of the members 10^e . (See Fig. 6.) When in this position, a fixed fulcrum for the jaw A is provided and the jaw held to swing freely in a horizontal plane.

When the jaw A is turned into its locked position, the parts a^6 a^6 bear against the edges e of the projections 10^e and assist in taking off a too great strain on the inner concaved edge of the said projections 10^e and said jaw cannot be removed from the head; but when the pin C is removed the jaw A can be swung out, so its fulcrum parts a^5 a^5 will disengage and pull away from the member 10^e . (See Fig. 6.)

So far as described it will be readily understood during a coupling action on a straight-way track the opposing jaws A will be swung inward until the portions A^5 pass from under the locking-blocks 11, which then drop in front of said jaw portions and securely hold them locked to a coupling position. In some instances, especially on curves, the coupling-jaws sometimes do not swing back to their innermost position, and to provide for locking them in a coupled position under such circumstances the gravity-block will drop into engagement with the depression a^x in the said jaws, it being obvious that as soon as the opposing jaws come in a like longitudinal plane and full back pressure is applied to them they will swing inward sufficiently to permit the blocks 11 dropping entirely down.

In my present type of coupler I have formed the draw-bar of sections and provided means whereby the draw-head is normally held in a proper longitudinal direction and yet permitted to turn laterally in either direction under spring tension.

To prevent the jaw A from swinging out too far and loosing its proper fulcrum-bearing when set to its uncoupled position, the under side of the inner end of the jaw has a segmental channel a^7 , that terminates in a stop-shoulder a^8 , adapted to coöperate with a stop-pin C, detachably held on the bottom of the draw-head mortise, as best shown in Figs. 3, 6, and 7, a spring-key being provided for engaging the pendent end of said pin C. When the pin C is in position, the outward swing of the coupling-jaw is thereby limited to the more readily adapt the coupling-jaws for a perfect interlocking when turning curves. For such purpose the draw-head is formed

with a short draw-bar section 15, the end of which terminates in a $\angle$ edge 15^a . The upper and lower faces of the section 15 are cast with transverse depressions 15^c , the rear edges of which have a middle part c^x , disposed transversely of the member 15, and rearwardly-inclined portions $c' c'$. The front portions of the depressions are formed with curved projecting lips or flanges c^3 , that lie in a plane with the top and bottom faces of the said member 15. At a point between the straight edges c and the $\angle$ end the member has upwardly and downwardly extending elongated stud-heads 16, disposed transversely and having undercut or beveled ends, the reason for which will presently appear. The studs 16 16 may be integrally formed with the member 15; but I prefer to make said studs 16 of two bolt-like sections having non-circular shanks to fit the correspondingly-shaped aperture 15^x in the part 15. The members 16 and 16^y are held together by a rivet 16^x , as shown in Fig. 11.

D designates a stout J-shaped strap-iron adapted to fit over one of the cross-beams of the car. Pivotedly mounted between the members $d d$ of the strap D is a tension-block 17, the two being relatively connected to permit of independent lateral motion thereof. The outer end of the block 17 has a central $\angle$ -shaped bearing-surface adapted to seat and rock laterally on the correspondingly-shaped opposing end 15^a of the draw-bar section 15, and to maintain a firm connection of the two parts 15 and 17 the block 17 is slotted longitudinally, as indicated by 17^a , through the rear end of which the stud or bolt 18, on which the block 17 is fulcrumed, passes.

19 designates a stout coiled spring held with the slot 17^a , with one end bearing against the bolt 18 and the other end against the front end of block 17, the tension of said spring and its position being such as to press the rear end of the block normally against the bolt 18 and the front end into contact with the stub end 15 of the draw-bar, and thereby maintain the two members 17 and 15 normally in a longitudinal plane.

To further hold the several parts constituting the draw-bar in a longitudinal direction, the front ends of the members $d d$ have longitudinally-elongated slots $d' d'$, adapted to slip over the headed studs 16 16, and by reason of the spring tension on the block 17 and transverse position of the stud-heads said members $d d$ become interlocked with said studs, and thereby form a convenient and simple means for maintaining the several parts of the draw-bar in a proper longitudinal alignment under ordinary conditions. To further maintain a substantially rigid connection of the several parts constituting the draw-bar, the front end of the members $d d$ are formed with enlargements d^x , adapted to seat in the depressions 15^b , and with curved lips or flanges d^5 , adapted to ride under the curved flanges or lips c^3 , as

clearly shown in Figs. 2, 9, 10, and 12, and to keep the two parts constituting the draw-bar properly in a straight line under ordinary conditions the enlargements d^x of the strap members d have transverse edges d^y held to bear against the straight edge c^x of the depressions 15° , it being obvious that by having rearwardly - inclined portions $c' c'$ merging with the central edge c^x ample means is provided for the end bearings for the parts d^x when the draw-head is swung laterally to each side, the several parts being always retained in a proper coöperative position by reason of the lips or flanges c^y and the flanges d^y . To separate the head, with its draw-bar section 15, from the straps or to attach thereto, it is only necessary to bring the straps at right angles to the member 15 and press against the rear end of the strap member D, which will cause its ends having the elongated apertures to automatically become disengaged from the studs 16, 16.

From the foregoing description, taken in connection with the accompanying drawings, it is believed the complete operation of the several parts of my invention and the advantages thereof will be readily apparent.

The several parts are especially designed for effecting an economical construction of the draw-head, the bar, and the coupling devices, all of which have a special coöperation and combine to produce a complete and effectively operating coupling means, the several parts of which are arranged for automatic action, the only manual labor required being to set the lock-block 11 to its elevated position when the parts are to be uncoupled.

While I prefer to use the special construction of draw-head shown and described, yet I desire it understood that my invention can be used in connection with other types of draw-heads.

The draw-head devices shown and described form subject-matter of a copending application filed by me May 8, 1902, Serial No. 106,394.

Having thus described my invention, what I claim, and desire to secure by Letters Patent, is—

1. The combination with a draw-bar, comprising a J-shaped strap, a bearing-block,

held between the ends thereof, and having yielding movement lengthwise thereof; of a draw-head having a shank, said shank and the bearing-block having pivotal coacting bearing-surfaces, and means for detachably connecting the draw-head shank with the ends of the J-shaped draw-bar, as and for the purposes shown and described. 55

2. The combination with the draw-head, having a shank terminating in a <-shaped bearing end, said shank also having a coöperating pivot-stud on the upper and under sides, transversely-disposed bearing-shoulders, and angle shoulders on the said upper and under sides; of a J-shaped draw-bar, having slotted ends to engage the pivot-studs on the draw-bar shank, and having transverse bearing-surfaces to engage the transverse and angle bearing-surfaces on the aforesaid shank, and the spring-held bearing-block mounted within the draw-bar members, said block having $\geq$ -shaped bearing-face opposing the $\geq$ -shaped end of the draw-head shank, all being arranged substantially as shown and described. 60 70 75

3. In a car-coupler, the combination with the draw-head formed with a shank having a <-shaped end bearing, a headed stud upon the upper and lower sides, adjacent the end bearing, and a projecting flange or lip on the said upper and lower faces, curved in transverse direction; of the J-shaped draw-bar strap, having elongated slots, adapted to co-operate with the aforesaid headed studs, the extremities of said strap having curved members to slide under the curved lips or flanges on the draw-head shank, the bearing-block, longitudinally movable in the J-shaped strap or bar, said block having a W-shaped end bearing to oppose the V-shaped bearing of the draw-head shank, and provided with a longitudinal slot, the cross pin or bolt for joining the block and the strap and the spring in said slot, all being arranged substantially 80 85 90 95 in the manner and for the purposes shown and described.
